(57) **CLAIM**

The ornamental design for an automobile, as shown and described.

DESCRIPTION

FIG. 1 is a front right perspective view of an automobile showing our new design;

FIG. 2 is a rear right perspective view thereof;

FIG. 3 is a front left perspective view thereof;

FIG. 4 is a rear left perspective view thereof;

FIG. 5 is a front view thereof;

FIG. 6 is a rear view thereof;

FIG. 7 is a top view thereof;

FIG. 8 is a right side view thereof; and,

FIG. 9 is a left side view thereof.

The claimed design is indicated by the relatively dark portions in the figures. The relatively light portions form no part of the claimed design.
